REFRIGERATING APPARATUS

Lawrence A. Philipp, Detroit, Mich., assignor to
 Kelvinator Corporation, Detroit, Mich., a corporation of Michigan

Application November 29, 1933, Serial No. 700,273

8 Claims. (Cl. 62—4)

The present invention relates to refrigerating systems and particularly a refrigerating system in which the cooling element is maintained normally at a predetermined temperature and in 5 which the cooling element is rendered temporarily more effective for hastening refrigeration.

One of the objects of the present invention is to provide an improved refrigerating system in 10 which the cooling element is rendered more effective automatically in response to a demand for quick refrigeration.

In furtherance of this object, it is another object of the present invention to restore the refrigerating system to its normal operation after 15 the demand for hastened refrigeration is satisfied.

A further object of the invention is to provide a refrigerating system in which a controller 20 thereof operates to maintain the cooling element normally at a desired temperature and, in which a separate thermostat, which is responsive to a commodity to be cooled, operates to modify temporarily the characteristics of the controller so 25 that the controller operates to cause the cooling element to hasten its refrigerating effect on the commodity.

Further objects and advantages will be apparent from the following description, reference 30 being had to the accompanying drawing where-in a preferred form of embodiment of the present invention is clearly shown.

In the drawing:

Fig. 1 is a diagrammatic view of my improved 35 refrigerating system, and

Fig. 2 is a front view of a refrigerator to which my improved system is particularly applicable.

For the purpose of illustrating one use of the improved refrigerating system, there is shown, in 40 Fig. 2, an insulated refrigerator cabinet 20 of the household type having a storage compartment 21 below which there is disposed a machine compartment, the door of the latter compartment being indicated at 22. The door 23 of the storage 45 compartment is shown open. A cooling element or heat absorbing means, herein shown as comprising an evaporator 25, is disposed within the storage compartment and the heat dissipating element, herein shown as comprising a compressor 26, a condenser 27 and a motor 28, are disposed within the machine compartment.

The evaporator 25 is formed of a plurality of concentric sheets of metal joined at intervals and also a lower inlet header 30 and an upper outlet header 31. Vaporized refrigerant which is

withdrawn from the upper header 31 by the compressor through a suction pipe 32, is compressed and forced into the condenser 27 by the compressor. The refrigerant is condensed in the condenser 27 and passes by way of pipe 35 to the receiving chamber 36 of a high-side-float type expansion valve 37. The outlet valve 38 of expansion valve 37 is controlled by a float 39 which rises to permit the escape of refrigerant when a certain quantity of liquid refrigerant collects in 10 chamber 36. From chamber 36, the refrigerant flows through pipe 41 to the lower header 30 of evaporator 25.

The motor 28 drives the compressor 26 through a belt 43 and the circuit to the motor is controlled 15 by a switch 44. The circuit to the motor 28 includes a wire 45, a stationary contact 46, a movable contact 47, a stationary contact 48, a wire 49, the motor 28 and a wire 50.

The temperature within the storage compartment 21 is of course responsive to the temperature of the evaporator 25 and for the purpose of maintaining a desired temperature, I have for illustrative purposes, disclosed a system in which the temperature of the evaporator is governed by controlling the duration of operation of the compressor 26, and the switch 44 is utilized for starting and stopping the compressor motor 28.

Switch 44, which is diagrammatically shown for the sake of clearness, comprises a frame 52 having platforms 53 and 54 which support metallic bellows 55 and 56 respectively. Two main levers 57 and 58 are pivotally mounted at 59 and 60 and are arranged to be moved upwardly by bellows 55 and 56 respectively. A coil spring 62 is interposed between the top of lever 57 and a movable abutment 63. This abutment 63 is screw threaded into a top platform 64 of frame 52 and can be turned by hand for adjusting the tension of spring 62. Lever 57 includes an upright arm 66 which arm provides bearings for knife edge end portions on levers 67 and 68 of a snap acting mechanism. Stops 70 and 71 limit the upward movement of levers 67 and 68, and a stop 72 limits the downward movement of lever 67. Lever 45 68 carries the movable contact 47 and the engagement of this contact with contacts 46 and 48 limits the downward movement of lever 68. A coil spring 74 is connected between levers 67 and 50 68 and normally tends to hold the levers in the position shown in which contact 47 bridges contacts 46 and 48 or in a position in which the levers engage stops 70 and 71 in which latter position, the contacts are separated.

The platform 53 of frame 52 provides an up- 55

right bearing 75 for a sliding rod 76 which rod rests on the top of lever 58 and is arranged to be moved upwardly thereby. The upper end of rod 76 engages the underside of lever 57 and is arranged to be moved downward by said lever. Rod 76 provides bearings for knife edge end portions on levers 78 and 79 and these levers are arranged to abut upper stops 81 and 82 and lower stops 83 and 84 respectively and a coil spring 85 tends to hold the levers against either the lower or upper stops. A coil spring 86 is connected with the end of lever 58 and a bolt 87 and the bolt can be adjustably set to govern the tension of spring 86. Bellows 55 is connected by a tube 89 with a bulb 90 and this system contains a volatile fluid which expands and contracts with increase and decrease in temperature. Bellows 56 is connected by a tube 91 with a bulb 92 and this system also contains a volatile fluid.

20 The adjustment of the spring 86 is such that during normal operation, bellows 56 is retracted and the end of rod 76 is below the path of movement of lever 57 and is therefore ineffective. The compressor 26 being operative, it will cause 25 a decreasing in temperature of the evaporator 25 and when the temperature is lowered to the desired minimum, pressure within the bulb 90, tube 89 and bellows 55 will be decreased sufficient to cause the knife edge bearings of upright 66 to 30 be lowered to below its dead center position with respect to levers 67 and 68 and the spring 74 will snap the switch open to thereby separate contact 47 from 46 and 48 and thus break the motor circuit. The evaporator will then gradually increase 35 in temperature and when the temperature attains a predetermined high value, the pressure in bellows 55 will cause the bellows to move the upright to snap the contacts closed.

The spring 62 is adjusted so that the system 40 operates to maintain the desired mean temperature in the storage compartment 21 of cabinet 20. Under this condition, water or the like, will gradually freeze within the evaporator 25. For this purpose shelves 94 are disposed in the evaporator 45 25 for carrying ice trays or the like 95. At times it is desirable to hasten refrigeration for example when it is desirable to quickly freeze water or congeal a dessert. In that event, the commodity to be refrigerated is placed on the shelf to which 50 the bulb 92 is bonded. The heat from the commodity will cause an immediate rise in temperature and pressure of the fluid within bulb 92 and consequently the bellows 56 will expand sufficiently to snap the rod 76 to the position shown in 55 the drawing. If the electrical snap switch is not already closed, rod 76 will cause the closing of the same. Thus it will be understood that the rod 76 will resist the movement of the switch toward contact opening position and therefore cause a 60 prolonged operation of the compressor and a lowering of the temperature of the evaporator below normal. The tension of the springs 85 and 86 may be such that the pressure within bellows 56 must recede to a pressure substantially equal 65 to the congealing temperature of the commodity so that the resistance of rod 76 is not overcome and the compressor will continue to operate until the commodity is congealed. After the pressure in bellows 56 recedes to its predetermined minimum, the lever 57 will move the rod 76 beyond 70 its dead center position whereby said rod will no longer be effective and the system is then automatically restored to the normal control of thermostat bulb 90.

75 It is apparent from the foregoing that I have

provided a refrigerating system wherein a temperature is maintained for normal refrigeration and I have provided for automatically hastening refrigeration in accordance to the direct demand of a commodity which is to be refrigerated quickly and I have provided for automatically restoring the system to its normal operation after the demand for quick refrigeration has been satisfied. 5

While the form of embodiment of the present invention as herein described constitutes a preferred form, it is to be understood that other forms might be adopted, all coming within the scope of the claims which follow.

I claim:

1. A refrigerating system comprising in combination a cooling unit, means for circulating a refrigerating medium through said unit, cyclical control apparatus including a thermo-bulb associated with said cooling unit for normally controlling the flow of said medium, a thermostat 20 arranged to be responsive primarily to the temperature of commodity placed in said cooling unit, and means actuated by said thermostat when the thermostat responds primarily to the temperature of the commodity in said cooling 25 unit for temporarily modifying the operation of said control apparatus.

2. A refrigerating system comprising in combination a cooling unit, means for circulating a refrigerating medium through said unit, cyclical 30 control apparatus including a thermo-bulb associated with said cooling unit for normally controlling the flow of said medium, a thermostat arranged to be responsive primarily to the temperature of commodity placed in said cooling 35 unit, and means actuated by said thermostat when the thermostat responds primarily to the temperature of the commodity in said cooling unit for temporarily modifying the operation of 40 said control apparatus, said last means including means operated automatically after a predetermined modified operation of said control apparatus for restoring the system to the normal control of said control apparatus.

3. A refrigerating system comprising in combination a cooling unit, having a tray supporting shelf therein, means for circulating a refrigerating medium through said unit, control apparatus including a thermo-bulb associated with said cooling unit for normally controlling the flow of 50 said medium, and thermostatic means in immediate thermal association with said shelf for temporarily modifying the operation of said control apparatus in response to temperature of commodity placed on said shelf. 55

4. A refrigerating system comprising in combination a cooling unit, having a tray supporting shelf therein, means for circulating a refrigerating medium through said unit, control apparatus including a thermo-bulb associated 60 with said cooling unit for normally controlling the flow of said medium, and thermostatic means in immediate thermal association with said shelf for temporarily modifying the operation of said control apparatus in response to temperature of 65 commodity placed on said shelf, said last means including means operated automatically after a predetermined modified operation of said control apparatus for restoring the system to the normal control of said control apparatus. 70

5. A refrigerating system comprising in combination a cooling unit, means for circulating a refrigerating medium through said unit, motive means for driving said first mentioned means, control apparatus including a thermo-bulb as- 75

sociated with said cooling unit to intermittently energize and deenergize said motive means for circulating said medium to maintain a normal temperature range, a thermostat arranged to be responsive primarily to the temperature of material placed in said cooling unit, and means actuated by said thermostat for temporarily modifying the operation of said control apparatus.

10 6. A refrigerating system comprising in combination a cooling unit, means for circulating a refrigerating medium through said unit, motive means for driving said first mentioned means, control apparatus including a thermo-bulb associated with said cooling unit to intermittently energize and deenergize said motive means for circulating said medium to maintain a normal temperature range, a thermostat arranged to be responsive primarily to the temperature of material placed in said cooling unit, and means actuated by said thermostat for temporarily modifying the operation of said control apparatus, said last means including means operated automatically after a predetermined modified operation of said control apparatus for restoring the system to the normal control of said control apparatus.

20 7. A refrigerating system comprising in combination an evaporator having a tray supporting shelf therein, a compressor for withdrawing refrigerant vapor from said evaporator, condensing the same and returning liquefied refrigerant thereto, an electric motor for driving the refrigerant compressor, a switch for energizing or deenergizing said motor, a thermostatic switch

actuating means including a thermo-bulb associated with said cooling unit for moving said switch to circuit making or breaking position to operate said compressor for maintaining a normal range of temperatures in said evaporator, modifying means associated with said thermostatic switch actuating means in normally disengaged relation thereto, and additional thermostatic means in immediate thermal association with said shelf for moving said modifying means to engaging position for temporarily modifying the normal operation of said switch in response to the temperature of the commodity placed on said shelf, said last means including means operated automatically after a predetermined modified operation of said control apparatus for restoring the system to the normal control of said control apparatus.

25 8. A refrigerating system comprising in combination, a cooling unit, means for circulating a refrigerating medium through said unit, a control element for said circulating means, a snap acting mechanism for moving said control element to either one of two extreme positions, means for applying a varying pressure to actuate said snap acting mechanism in accordance with a predetermined condition, means for modifying the operation of said first snap acting mechanism comprising a second snap acting mechanism disposed in normally disengaged relation adjacent thereto, and thermal means for actuating said second snap acting mechanism to engaging position for causing one abnormal operation of said control element.
